UNITED STATES PATENT OFFICE

2,322,064

CORING DEVICE

Benjamin W. Sewell, Tulsa, Okla., assignor to
Standard Oil Development Company, a corpora-
tion of Delaware

Application December 22, 1941, Serial No. 423,933

3 Claims. (Cl. 255—72)

The present invention is directed to a pressure coring device.

The principal object of the present invention is the provision of a device of the character described in which are provided means for cutting the core, a chamber for receiving the core as it is cut, and means for sealing off the chamber after the completion of the coring operation, including a valve actuated by a go-devil.

Other objects and advantages of the present invention will appear from the following detailed description of the accompanying drawing in which—

Fig. 1 is a vertical section of the upper portion of the device, and

Fig. 2 is a similar view of the lower portion.

Referring to the drawing in detail, numeral 1 designates a drill stem carrying at its lower end a drilling head 2 which is provided with circumferentially disposed cutters 3 for cutting the core, said cutters surrounding a central passage 4 through which the core passes as it is cut. Mounted in the head 2 is a rotatable valve 5 having a central passage 6 adapted to align with passage 4. This valve is carried by the lower end of a cylinder 7 and is of the type shown in Patent No. 2,216,962, issued October 8, 1940, in which is disclosed in detail the operating mechanism for this valve. The cylinder 7 has an opening 8 at its upper end through which passes a stem 9. The lower end of the stem carries a cone valve 10 which is adapted to the seat on the underside of opening 8. Carried by the stem 9 below the valve 10 is a barrel 11 having a lower open end adapted to communicate with passage 4 and being provided at its lower end with spring arms 12 constituting a core catcher.

Mounted in the drill stem above cylinder 7 is a second cylinder 13 having an upper compartment 14 and a lower compartment 15, separated by a partition 16 having a central opening 17, the lower portion of which constitutes a seat for a cone valve 18 carried by a stem 19 extending up through compartment 14 through a packing gland 20 and to the exterior where it terminates in a head 21.

The stem 9 extends through the bottom wall of compartment 15 and terminates in a piston 22. The lower wall of compartment 15 below the piston 22 is provided with inlet ports 23. Compartment 15 is normally filled with oil.

The coring device illustrated is lowered into the well with the parts in the position shown. Compartment 14 is filled with air at atmospheric

pressure or, if desired, may be partially evacuated. When the coring operation is completed, a weight 24 is dropped on the head 21. This weight may be dropped from the surface or it may be suspended in the drill stem by a wire line at a sufficient distance above the head so that, when it drops on the head, it will exercise enough force to move the stem 19 downwardly removing the valve 18 from its seat. The drilling mud which is used in the drilling operation enters the compartment 15 through the inlet ports 23 and exerts a pressure behind the piston 22. As soon as valve 18 is removed from its seat, the drilling mud pressure, which may be several thousand pounds, will immediately force the piston 22 upwardly into the compartment 15 carrying the stem 9 and the barrel 11 with it. The parts are so proportioned that the piston will travel a sufficient distance to seat the valve 10 thereby sealing off the upper end of chamber 7. As soon as the barrel 11 is withdrawn from the central passage of the valve 5, this valve is closed by the mechanism heretofore referred to and described in Patent No. 2,216,962. Chamber 7 is then completely sealed and is brought to the surface.

While the present invention has been described in connection with a drill stem core barrel, it will be apparent that it is also applicable to wire line core barrels. It is to be understood that various changes in design and relationship of parts are contemplated within the scope of the present invention, the embodiment above described being purely illustrative.

The nature and objects of the present invention having been thus described and illustrated, what is claimed as new and useful and is desired to be secured by Letters Patent is:

40. 1. A pressure coring device comprising a cutting head adapted to cut a core and having a central passage adapted to receive the core, a core-receiving barrel arranged behind said cutter head adapted to assume a forward position and a retracted position and arranged for communication with said passage when in its forward position, means for holding said barrel in its forward position during the coring operation, means operable by a falling weight to move said barrel to its retracted position upon completion of the coring operation, and means operable upon removal of said barrel to its retracted position for sealing said barrel under the pressure of the formation cored.
45. 2. A pressure coring device comprising a cut-

ting head adapted to cut a core and having a central passage adapted to receive the core, a core-receiving barrel arranged behind said cutter head adapted to assume a forward position and a retracted position, and arranged for communication with said passage when in its forward position, means for holding said barrel in its forward position including a piston under fluid pressure, means operable upon the completion of the coring operation for relieving the pressure on said piston and permitting the barrel to move to its retracted position, and means operable upon movement of said barrel to its retracted position for sealing said barrel under the pressure of the formation cored.

3. A pressure coring device comprising a cutting head adapted to cut a core and having a central passage adapted to receive the core, a core receiving barrel arranged behind said cutter head

adapted to assume a forward position and a retracted position and arranged for communication with said passage when in its forward position, means for holding said barrel in its forward position, including a piston rigidly connected to said barrel, a cylinder in which said piston works adapted to be filled with a fluid to hold said piston in its outermost position, said piston having its outer face exposed to a pressure at least as great as the pressure of the formation being cored; means for releasing the fluid from said cylinder whereby said piston is pushed into said cylinder by the pressure acting on the outer face and said barrel is moved to its retracted position, and means operable upon movement of said barrel to its retracted position for sealing said barrel under the pressure of the formation cored.

BENJAMIN W. SEWELL.
